US00D767490S

(12) **United States Design Patent** (10) **Patent No.:** **US D767,490 S**
Bose et al. (45) **Date of Patent:** **** Sep. 27, 2016**

(54) **BATTERY BUSHING**

(71) Applicants: **Johnson Controls Technology Company**, Holland, MI (US); **Johnson Controls Autobatterie GmbH & Co. KGaA**, Hannover (DE)

(72) Inventors: **Deepan Bose**, Milwaukee, WI (US); **Michael E. La Croix**, Mequon, WI (US); **William J. Ross**, Mukwonago, WI (US); **Anne-Laure Ledoux**, Langenhagen (DE)

(73) Assignees: **Johnson Controls Technology Company**, Holland, MI (US); **Johnson Controls Autobatterie GmbH & Co. KGAA**, Hannover (DE)

(**) Term: **14 Years**

(21) Appl. No.: **29/513,993**

(22) Filed: **Jan. 7, 2015**

(51) **LOC (10) Cl.** **13-02**

(52) **U.S. Cl.**

USPC **D13/119**

(57) **CLAIM**

The ornamental design for a battery bushing, as shown and described.

DESCRIPTION

FIG. 1 is a top perspective view of the ornamental design of the battery bushing;

FIG. 2 is a bottom perspective view thereof;

FIG. 3 is a left side elevation view thereof, the right side elevation view being a mirror image;

FIG. 4 is a front elevation view thereof;

FIG. 5 is a rear elevation view thereof;

FIG. 6 is a top view thereof;

FIG. 7 is a bottom view thereof; and,

FIG. 8 is a cross-sectional view taken along line **8-8** of FIG. 4.

The broken lines shown in the drawings are included for the purpose of illustrating environmental structure and form no part of the claimed design.

1 Claim, 4 Drawing Sheets
